LUMINOUS TUBE LIGHTING SYSTEM

Charles H. Bechler, Los Angeles, Calif., assignor
to Flame Lite Corporation, Los Angeles, Calif.,
a corporation of California

Application March 6, 1937, Serial No. 129,455

10 Claims. (Cl. 176—124)

This invention relates to a system for energizing luminous tubes, such as "neon" tubes now in common use for display purposes.

Tubes of this character have been made in the past; they usually have a filling of one or more of the noble monatomic gases, such as neon, argon, helium, krypton, etc. The filling usually has a pressure of about 10 to 15 millimeters of mercury, and a high ionizing potential difference is impressed upon the electrode terminals at the ends of the tube. The period of useful life of such tubes is extended. This long life is due to the use of a considerable amount of gas in the tube, evidenced by the gas pressure of 10 to 15 millimeters of mercury, as well as due to the use of large electrode areas in relation to the current flow, which may be of the order of 50 milliamperes.

The most practical source of energy for supplying tubes of this prior character is a constant current transformer. The tubes, although in reality reversing the current flow many times in each second through them (in accordance with the alternations of the electromotive force impressed across them), appear nevertheless to burn with a steady brilliance.

It has been proposed in the past to enhance the effect of the tube by causing it to flicker in an irregular manner, such as by causing the position of the luminous positive column of gas to alter in an erratic manner; and especially by causing the discharge to be unstable. In all such prior attempts, the overall luminosity of the tube is rather poor; this is due at least partially to the fact that such prior tubes must utilize a gas pressure much below the usual values of about 10 to 15 millimeters of mercury pressure, and sometimes as low as a few millimeters of mercury.

It is one of the objects of this invention to make it possible to operate luminous tubes at intense brilliance and in an unstable manner, and yet secure an extended tube life.

In order to secure these results, it has been found, as one of the essential requirements, to parallel the tube with a load that, in conjunction with the tube, forms a low power factor load for the source of electrical energy, such as the secondary of a transformer. This reduction in power factor may be optionally a capacitive or an inductive load; ordinarily it is more convenient to utilize an inductive rather than a capacitive load.

Another requirement is that the tube space for the gaseous content be irregular, as by placing within the tube, materials that interrupt the

tube column although leaving irregular interstices. Such material need not be dielectric, so long as they do not form short circuiting bridges; but one material may be a series of crumpled thin mica sheets, inserted within the tube.

It is accordingly still another object of this invention to provide a tube structure that includes crumpled sheets of thin material for enhancing the unstable character of the discharge.

Instead of providing a separate element for the parallel load to the tube, it is feasible so to construct the transformer that the secondary overall load thereon has the requisite low power factor, as by providing leakage in the magnetic circuit. It is accordingly another object of this invention to provide a transformer adapted to operate a tube of the character defined, in an unstable manner.

This inherent instability, in conjunction with the large current flow in the tube, causes a very striking appearance, not unlike that of a flame of intense brilliance within the tube.

This invention possesses many other advantages, and has other objects which may be made more easily apparent from a consideration of several embodiments of the invention. For this purpose there are shown a few forms in the drawing accompanying and forming part of the present specification. These forms will now be described in detail, illustrating the general principles of the invention; but it is to be understood that this detailed description is not to be taken in a limiting sense, since the scope of the invention is best defined by the appended claims.

Referring to the drawing:

Figure 1 is a diagram of a system incorporating the invention;

Figs. 2, 3, and 4 are diagrams similar to Fig. 1 of modified forms of the invention; and

Fig. 5 is an enlarged sectional view of a luminous tube utilized in connection with the invention.

The luminous tube 1 is shown of indefinite length and its configuration may conform with any desired design, such as letters or borders of signs. The luminous tube is preferably made of transparent material, such as glass or "Pyrex" glass, provided with electrodes 2 and 3 at the ends thereof, whereby the electrical energy may be conducted to the tube 1.

Preferably the filling of the tube comprises one or more of the noble monatomic gases, such as neon, argon, helium, etc., although slight admixtures of other gases or vapors may be used, such as mercury.

In ordinary tubes of this character the size may vary from as little as 6 millimeters external diameter to as high as 40 or 50 millimeters external diameter; and the gas pressure within the tube is ordinarily from 10 to 12 millimeters of mercury. The quantity of gases thus present in the tube 1 is considerable and the life of the tube is therefore enhanced even upon a large current flow of the order of 120 milliamperes or more.

By the aid of the present invention, an unstable discharge is secured through the tube and of considerable brilliancy, producing a flame-like effect. In order to secure this result, it is first of all essential to provide a tortuous path for the discharge in the tube 1. This is preferably accomplished by inserting within tube 1 pieces of crumpled up thin sheets of mica, such as illustrated by reference character 4 in Fig. 5. Other materials, dielectric or conducting, might be used, so long as they do not form continuous circuits within the tube. The reflecting quality of the mica sheets 4 together with the tortuous path thus provided for the luminous positive column enhance the brilliancy of the discharge. This effect of brilliancy is still more marked by the irregular and unstable flame-like path of the discharge around and about the crumpled obstructions.

It is the main purpose of this invention to secure this instability even when the tube is brilliantly lighted by a current flow of 120 milliamperes or greater. For this purpose it has been discovered that the instability of the discharge can be easily secured by paralleling the tube 1 with a supplemental load 5 so as to make the combination of tube 1 and load 5 have a power factor in the neighborhood of 20 to 30 per cent. This low power factor load 5 may be either capacitive or inductive. Apparently due to this parallel connection and the continual cyclic lighting and extinguishing of the tube 1 by supplying alternating current to the electrodes 2 and 3, the discharge incessantly flickers from one tortuous path to the other throughout the length of the tube.

In the form shown in Fig. 1 the source of electrical energy is indicated as a constant current transformer 6, the primary of which may be shunted by a condenser 7, sufficient to correct the power factor on the primary side of the transformer 6.

It has been found that the low power factor load 5 and the energizing transformer 6 may readily be combined in one structure. Such a form is illustrated in Fig. 2. In this case the energizing transformer is fed from the mains 8. The source is provided with a laminated iron core 9 upon which are wound the primary and secondary windings. The primary winding in this instance is shown as comprising the three sections 10, 11 and 12 in series and on separate portions of the core 9. The secondary winding comprises three corresponding sections 13, 14 and 15 placed in this instance in parallel and across the luminous tube 1. In order to provide the low power factor shunting load, the core 9 is provided with magnetic leak paths between the sections so as to increase the leakage flux between the primary and secondary. Thus for example poles 16 and 17 may extend from the main body of the core 9 to form a narrow air gap intermediate the sections 10 and 13. Similar poles 18 and 19 are provided for the sections 11 and 14 and poles 20 and 21 for the sections 12 and 15.

The effect of the leakage paths thus provided is to increase the stray inductance in the transformer to such an extent as to reduce the power factor of the load supplied by the secondary side of the transformer to the desired low value. It has been found that by appropriate choice of air gaps the power factor can be reduced to the requisite value of 20 to 30 per cent.

In the form of the invention illustrated in Fig. 3 the parallel load is shown as formed by a pair of coils 22 and 23 having an iron core 24. The coil 22 is connected across the terminals of the tube 1 and in order to increase the inductance of this parallel load the coil 23 may be connected to an appropriate source of alternating current.

In still another form of the invention illustrated in Fig. 4, the secondary winding 25 of the iron cored transformer 26 may be connected across the terminals of the tube 1. The primary winding 27 may be connected to a source of alternating current. In this case the low power factor is secured by the aid of a magnetic shunt 28 between the winding 25 and 27. On this shunt 28 may be wound a short circuited coil 29 to increase the inductive reactance.

In all of the forms disclosed, the important characteristic is the supplying of the luminous tube 1 from a source, and so loading the source in parallel with the tube, as to produce a low power factor; and further, in the provision of a tortuous path for the discharge within the tube 1. When these factors are present, the tube 1 may be illuminated very intensely with a relatively high current flow of 50 milliamperes or greater. There is a rapid intense unstable discharge which persists over long periods of use. The instability is not destroyed by the use of the comparatively high gaseous pressure mentioned, such as 10 or 12 millimeters of mercury.

What is claimed is:

1. A luminous discharge tube, having material therein to give a tortuous path for the discharge, means for energizing the tube, and a load paralleling the tube to reduce the power factor of the combination of the tube and the load to a value no greater than thirty percent.

2. A luminous tube having a gaseous filling, and thin sheets of crumpled material within the tube.

3. A luminous tube having a gaseous filling of a pressure neighboring ten millimeters of mercury, and thin sheets of crumpled material within the tube.

4. A luminous tube, thin sheets of crumpled material in the tube, means for energizing the tube, and a load paralleling the tube to reduce the power factor of the combination of the tube and the load.

5. A luminous discharge tube, said tube having material therein to give a tortuous path for the discharge, as well as, a noble monatomic gaseous filling of a pressure neighboring ten millimeters of mercury, means for energizing the tube, and a load paralleling the tube to reduce the power factor of the combination of the tube and the load, to a value not greater than thirty percent.

6. A luminous tube of the noble monatomic gas type, said tube having a gas pressure of about ten millimeters of mercury, and capable of operating under a load of about 120 milliamperes, as well as having therein material for providing a tortuous path for the discharge, and means for energizing said tube, said energizing means having provisions for paralleling the tube load with

a load so that the combined parallel loads have a power factor no greater than thirty percent. 7. A luminous discharge tube having material therein to provide a tortuous path for the discharge, and a transformer for energizing said tube, said transformer having a primary and a secondary winding, as well as, an iron core, said windings and the core being so arranged that the total load on the secondary winding, including the tube, has a power factor no greater than thirty percent.

8. A luminous discharge tube in which there is a noble monatomic gaseous filling at a pressure of no less than ten millimeters of mercury, and having material therein to provide a tortuous path for the discharge, and a transformer for energizing said tube, said transformer having a primary and a secondary winding, as well as an iron core, said windings and the core being so arranged that the total load on the secondary

winding, including the tube, has a power factor no greater than thirty percent.

9. A luminous discharge tube having crumpled mica sheets therein to provide a tortuous path for the discharge, and a transformer for energizing said tube, said transformer having a primary and a secondary winding, as well as an iron core, said windings and the core being so arranged that the total load on the secondary winding, including the tube, has a power factor no greater than thirty percent. 5

10. A luminous tube, means for energizing the tube, and a load fed by the energizing means and paralleling the tube to reduce the power factor of the combination of the tube and the load, said load comprising a pair of coils and an iron core for the coils, one of said coils shunting the tube, and the other coil being energized by an alternating current. 15
